US0D1009996S

(12) **United States Design Patent** (10) Patent No.: **US D1,009,996 S**
(45) Date of Patent: ** Jan. 2, 2024

(54) **FOLDER**

(71) Applicant: **Ideastream Consumer Products, LLC**,
Cleveland, OH (US)

(72) Inventor: **Eric Fitzgerald Klosky**, Chagrin Falls,
OH (US)

(73) Assignee: **Ideastream Consumer Products, LLC**,
Cleveland, OH (US)

(**) Term: **15 Years**

(21) Appl. No.: **29/723,744**

(22) Filed: **Feb. 10, 2020**

(57) CLAIM

I claim the ornamental design for a folder, as shown and described.

DESCRIPTION

FIG. 1 is a front/right/top perspective view of a first embodiment of the folder;
 FIG. 2 is a front elevational view thereof;
 FIG. 3 is a rear elevational view thereof;
 FIG. 4 is a top plan view thereof;
 FIG. 5 is a bottom plan view thereof;
 FIG. 6 is a left-side elevational view thereof; and

FIG. 7 is a right-side elevational view thereof.
FIG. 8 is an front/left/top perspective view thereof in a curled state.
A second embodiment of the folder is a mirror image of the folder shown in the first embodiment with FIGS. 1-5 being mirrored vertically and FIGS. 6-7 being mirrored horizontally.
FIG. 9 is a front/right/top perspective view of a third embodiment of the folder;
FIG. 10 is a front elevational view thereof;
FIG. 11 is a rear elevational view thereof;
FIG. 12 is a top plan view thereof;
FIG. 13 is a bottom plan view thereof;
FIG. 14 is a left-side elevational view thereof; and
FIG. 15 is a right-side elevational view thereof.
FIG. 16 is an front/left/top perspective view thereof in a curled state.
A fourth embodiment of the folder is a mirror image of the folder shown in the third embodiment with FIGS. 10-13 being mirrored vertically and FIGS. 14-15 being mirrored horizontally.
FIG. 17 is a front/right/top perspective view of a fifth embodiment of the folder;
FIG. 18 is a front elevational view thereof;
FIG. 19 is a rear elevational view thereof;
FIG. 20 is a top plan view thereof;
FIG. 21 is a bottom plan view thereof;
FIG. 22 is a left-side elevational view thereof; and
FIG. 23 is a right-side elevational view thereof.
FIG. 24 is an front/left/top perspective view thereof in a curled state.
A sixth embodiment of the folder is a mirror image of the folder shown in the fifth embodiment with FIGS. 18-21 being mirrored vertically and FIGS. 22-23 being mirrored horizontally.
FIG. 25 is a front/right/top perspective view of a seventh embodiment of the folder;
FIG. 26 is a front elevational view thereof;
FIG. 27 is a rear elevational view thereof;
FIG. 28 is a top plan view thereof;
FIG. 29 is a bottom plan view thereof;
FIG. 30 is a left-side elevational view thereof; and

FIG. 31 is a right-side elevational view thereof.
FIG. 32 is a front/left/top perspective view thereof in a curled state.
FIG. 33 is a front elevational view thereof, with the gusset in an extended state.
An eighth embodiment of the folder is a mirror image of the folder shown in the seventh embodiment with FIGS. 26-29 being mirrored vertically and FIGS. 30-31 being mirrored horizontally.
FIG. 34 is a front/right/top perspective view of a ninth embodiment of the folder;
FIG. 35 is a front elevational view thereof;
FIG. 36 is a rear elevational view thereof;
FIG. 37 is a top plan view thereof;
FIG. 38 is a bottom plan view thereof;
FIG. 39 is a left-side elevational view thereof; and
FIG. 40 is a right-side elevational view thereof.
FIG. 41 is an front/left/top perspective view thereof in a curled state.
FIG. 42 is a front elevational view thereof, with the gusset in an extended state.
A tenth embodiment of the folder is a mirror image of the folder shown in the ninth embodiment with FIGS. 35-38 being mirrored vertically and FIGS. 39-40 being mirrored horizontally.
FIG. 43 is a front/right/top perspective view of an eleventh embodiment of the folder;
FIG. 44 is a front elevational view thereof;
FIG. 45 is a rear elevational view thereof;
FIG. 46 is a top plan view thereof;
FIG. 47 is a bottom plan view thereof;
FIG. 48 is a left-side elevational view thereof; and
FIG. 49 is a right-side elevational view thereof.
FIG. 50 is an front/left/top perspective view thereof in a curled state; and
FIG. 51 is a front elevational view thereof, with the gusset in an extended state.
A twelfth embodiment of the folder is a mirror image of the folder shown in the eleventh embodiment with FIGS. 44-47 being mirrored vertically and FIGS. 48-49 being mirrored horizontally.
